ATTORNEY

UNITED STATES PATENT OFFICE.

FRANK CALVO, OF WATERBURY, CONNECTICUT.

CALLOUS PROTECTOR.

Application filed May 16, 1927. Serial No. 191,671.

This invention relates to foot appliances, and more particularly to a protecting device for callouses or other abnormal conditions upon the sole of a foot.

5 One object of this invention is to provide a callous protector adapted to be accurately adjusted to the size of a foot and to the position of a callous upon said foot.

A further object is to provide a callous 10 protector of this nature which will be simple in construction, inexpensive to manufacture, easy to manipulate, compact, ornamental in appearance, and very efficient and durable in use.

15 With these and other objects in view there have been illustrated on the accompanying drawings two forms in which the invention may be conveniently embodied in practice.

Fig. 1 represents a plan view of the first 20 embodiment of the invention.

Fig. 2 is a sectional view of the same, taken along the line 2—2 of Fig. 1, looking in the direction of the arrows.

Fig. 3 is a sectional view of the same, taken 25 along the line 3—3 of Fig. 1, looking in the direction of the arrows.

Fig. 4 is a side view of a human foot, showing one of the callous protectors in operating position.

30 Fig. 5 is a bottom plan view of a modified form of callous protector having an extensible front strip.

Fig. 6 is a perspective view of the extensible front strip shown in Fig. 5.

35 Fig. 7 is a sectional view taken along the line 7—7 of Fig. 5, looking in the direction of the arrows.

Referring now to the drawings in which like reference numerals denote corresponding 40 parts throughout the several views, the numeral 10 indicates a callous protecting pad of leather, rubber, or other suitable cushioning material adapted to be located under the sole of a foot 11 just in the rear of the position of a callous 12. The pad 10 is preferably made substantially rectangular in shape with flat top and bottom surfaces 13 and 14. The corners 15 of the pad 10 are curved as shown in Fig. 1, and the top edges 16 thereof are rounded as shown in Fig. 3, whereby a smooth surface will be presented, and all possibility of scratching or otherwise injuring the foot will be avoided.

The pad 10 is provided on its under surface with a pair of spaced sockets 16^a adapted 50 to be held in alinement with a pair of

apertures 16^b in a metal base plate 17, the latter being permanently secured to the pad 10 in any suitable manner, as by rivets 17^a. A second metal plate 18 is pivotally secured 60 to said plate 17, as by a hinge 18^a, and is adapted to be detachably held in closed position parallel to said base plate 17 by a resilient catch member 19 formed integral with the base plate 17.

65 In order to maintain the leather pad 10 in the proper adjusted position within a shoe 20, provision is made of an elongated relatively stiff base strip 21 preferably constructed from thin metal and having curved ends 22 and 23. The base strip 21 is adapted to be located between the base plate 17 and the hinged plate 18, as shown in Figs. 1 and 3. The base strip 21 has a plurality of spaced apertures 24 which are adapted to 70 be brought into alinement with the pair of sockets 16^a in the pad 10 and the apertures 16^b, so that when the hinged plate 18 is moved into closed position adjacent the base plate 17, a pair of tapered eyelets 18^a on said hinged plate 18 will pass through the two apertures 24 of the base strip 21 which are in alinement with the apertures 16^b in the base plate 17 and will extend a short distance inside said sockets 16^a. By means of 75 this construction, the pad 10 will be detachably locked in any desired adjusted position along the length of the base strip 21.

80 In order to prevent the possibility of injury to the stocking or foot of the user, and also to render the device more comfortable when worn in a shoe, the base strip 21 is covered with a protecting cloth 25 having its edges secured together as by a row of stitching 85 26, as clearly shown in Figs. 2 and 3.

85 In order to cushion the heel of the foot, a substantially semi-circular heel pad is mounted on the rear of the base strip 21. This heel pad comprises a top stiff leather plate 26^a and a lower flexible leather disc 26^b secured to the plate 26^a in any suitable manner, as by a suitable adhesive. The rear end of the base strip 21 is adapted to be frictionally held between the top plate 26^a 100 and the lower disc 26^b.

105 In operation, the callous protector will be placed within the shoe 20 under the foot 11 with the protecting pad 10 adjusted to the proper position just in the rear of the callous 12, as shown in Fig. 4. It will thus be seen that the weight of the foot will be kept 110 off the callous 12, permitting the blood to

circulate therein and enabling the abnormal condition to be rapidly cured.

In the modified form of the invention shown in Figs. 5 to 7, a pad 27 is provided which is similar in all respects to the pad 10 previously described. The base strip in this instance, however, is made in two overlapping sections 28 and 29 which are relatively slidable, so as to permit the callous protector to be readily adjusted to fit various sizes of shoes. The front strip section 28 is provided at its rear end with a pair of upwardly and inwardly directed flanges 30 and 31 which are adapted to form a guide-way for the front part of the rear section 29. The sections 28 and 29 are provided with spaced perforations 32 and 33 which are adapted to be brought into alignment with each other so as to permit the pair of holding screws 34 to be inserted therethrough for holding the sections 28 and 29 and the protecting pad 27 in their proper adjusted positions.

In order to provide a cushion for the heel of the foot, a heel pad is provided. This heel pad, as shown in Fig. 5, comprises a top stiff plate 35 adapted to lie above the strip section 29 and a lower flexible plate 36 adapted to lie under the section 29. The plates 35 and 36 are preferably substantially semi-circular and constructed of leather. They are adapted to be held securely together by a row of stitches 37, as shown in Figs. 5 and 7.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a callous protector adapted to be worn in a shoe under a foot, a stiff base strip adapted to rest upon the insole, a pad adjustably connected to said base strip, and

means for holding said pad in a position just behind the callous.

2. In a callous protector adapted to be worn in a shoe under a foot, a stiff base strip having a plurality of perforations spaced along its length, a pad adapted to rest upon said strip behind the callous, said pad having a pair of sockets adapted to be brought into alignment with two of the perforations of said strip, and means passing through said two perforations for joining said pad and said strip.

3. In a callous protector adapted to be worn in a shoe under a foot, a stiff base strip having a plurality of perforations spaced along its length, a pad adapted to rest upon said strip behind the callous, said pad having a plurality of sockets adapted to be brought into alignment with certain of the perforations of said strip, and means passing through said aligned perforations and into said sockets for joining said pad and said strip.

4. In a callous protector adapted to be worn in a shoe under a foot, a stiff base strip having a plurality of perforations spaced along its length, a pad adapted to rest upon said strip behind the callous, said pad having a socket adapted to be brought into alignment with one of the perforations of said strip, a hinged locking plate secured to said pad, and a lug on said hinged plate fitting said socket and passing through the strip perforation in alignment therewith for detachably joining said pad and said strip.

5. In a callous protector adapted to be worn in a shoe under a foot, a stiff base strip having a plurality of perforations spaced along its length, a pad adapted to rest upon said strip behind the callous, said pad having a socket adapted to be brought into alignment with one of the perforations of said strip, a hinged locking plate secured to said pad, and a tapered tubular lug on said hinged plate fitting said socket and passing through the strip perforation in alignment therewith for detachably joining said pad and said strip.

In testimony whereof, I have affixed my signature to this specification.

FRANK CALVO.
